HANDRAIL BRACKET

John R. Morgan, Chicago, Ill., assignor to Amerock Corporation, Rockford, Ill., a corporation of Illinois

Filed Nov. 2, 1961, Ser. No. 67,359

Term of patent 14 years

(Cl. D13—7)

FIGURE 1 is a perspective view, showing my new design for a handrail bracket.

FIG. 2 is a top view.

FIG. 3 is a side view of the handrail bracket.

FIG. 4 is a front view.

FIG. 5 is an enlarged sectional view taken along the line 5—5 in FIG. 3.

The design is particularly characterized by the flat surfaces of the arm in combination with the tapering of the arm and the shape of the mounting plate as best shown in FIGS. 1, 3 and 4.

I claim:

The ornamental design for a handrail bracket substantially as shown and described.
